CLAIM

(21) Appl. No.: **29/088,528**

The ornamental design for a clamp for attaching a computer game controller to a desktop, as shown and described.

(22) Filed: **May 26, 1998**

DESCRIPTION

(51) LOC (7) Cl. **14-02**

Cross-reference is made to commonly-assigned design application U.S. Ser. No. 29/088,527, filed on even date herewith, for clamp for attaching a computer game controller to a desktop, and utility application U.S. Ser. No. 09/085,338, filed on even date herewith for controller for games or simulation programs with clamp for desktop mounting.

(52) U.S. Cl. **D21/333**

FIG. 1 is a top, front, left perspective view of a clamp for attaching a computer game controller to a desktop, showing our new design.
